Forest Wilson, 6547 W. North Ave., Oak Park, Ill.

Filed Sept. 3, 1959, Ser. No. 57,420

Term of patent 14 years

(Cl. D15—11)

FIG. 1 is a front perspective view of a divan, showing my design;

FIG. 2 is a rear perspective view, showing the article in its extended position of use as a bed; and

FIG. 3 is an end elevational view of the article on an enlarged scale.

The dominant features of my design reside in the back rail support for the cushions in the end-to-end position of FIG. 1 and the adaptability of the cushions for edge-to-edge positioning to extend the length of the cushioned surface of the divan beyond the end of the back rail support.

I claim:

The ornamental design for a divan, as shown and described.
